CLAIM

The ornamental design for a tackle binder with hooks, as shown and described herein.

DESCRIPTION

FIG. 1 is a front elevation view of the tackle binder with hooks;

FIG. 2 is a rear elevation view of the tackle binder;

FIG. 3 is a left side elevation view of the tackle binder with hooks;

FIG. 4 is a right side elevation view of the tackle binder with hooks;

FIG. 5 is a top view of the tackle binder with hooks;

FIG. 6 is a bottom view of the tackle binder with hooks;

FIG. 7 is a right side perspective view of the tackle binder with hooks;

FIG. 8 is a left side perspective view of the tackle binder with hooks; and,

FIG. 9 is a perspective view of the tackle binder with hooks, in an open configuration.

The various components shown in broken line illustrations are shown in broken lines for illustrative purposes only and form no part of the claimed design.
